G. B. Fehley.

UNITED STATES PATENT OFFICE.

ROBERT L. DORSEY, OF INDIANAPOLIS, INDIANA, ASSIGNOR TO TUCKER & DORSEY MFG. CO., OF INDIANAPOLIS, INDIANA, A CORPORATION OF INDIANA.

TRUCK TIE PLATE.

Application filed June 20, 1923. Serial No. 646,536.

To all whom it may concern:

Be it known that I, ROBERT L. DORSEY, a citizen of the United States, residing at Indianapolis, in the county of Marion and State of Indiana, have invented a new and useful Truck Tie Plate, of which the following is a specification.

It is the object of my invention to tie a center brace of a platform truck economically and efficiently to the end braces thereof while permitting such center and end braces to be spaced apart to provide an intervening space, as for a caster-wheel bearing; and at the same time to strengthen the mounting of such caster-wheel bearing by the action of such braces and the tie between them.

The accompanying drawing illustrates my invention: Fig. 1 is a side elevation, in partial section, of a platform truck embodying my invention; Fig. 2 is a fragmental perspective view of the bottom of the truck, inverted, with the caster removed; Fig. 3 is an enlarged section on the line 3—3 of Fig. 1; and Fig. 4 is a plan of my tie plate before it is bent to its final form.

The truck shown is provided with the usual truck floor 10, side braces 11, end braces 12, and also the center brace 13 of Patent No. 1,209,408, issued to me on December 19, 1916. The ends of the center brace 13 are spaced from the end braces 12, to provide an intervening space at each end of the center brace. About midway longitudinally of the truck are two large side wheels 14; and about midway transversely at each end is a caster wheel 15.

Each caster wheel 15 is carried by a yoke or fork 16, rigid with a shank 17 free to rotate in a bearing casting 18. Each bearing casting is located in the intervening space between an end brace 12 and the adjacent end of the center brace 13, and has a base which is attached by clamping bolts 19 to the inner face of such end braces. It also has two vertically spaced ears 20 which project from said base toward and preferably against the adjacent end of the center brace, both to constitute bracing abutments therefor and to be braced thereby. These ears 20 are the spaced bearing for the shank 17.

A tie plate 22 is provided to rigidly secure each end of the center brace 13 to the end braces 12. I prefer to form this tie

plate of sheet metal, first cutting a slot 23 in one end thereof, bending up the other end of the plate to form a flange 24 which may be clamped against the outer face of the end brace 12 by at least the lower pair of 60 the bolts 19, and then bending up two ears 25 along oblique bending-lines into position to engage the sides of the center brace 13. The width of the slot 23 is preferably substantially equal to the thickness of the center 65 brace 13. I provide in the ears 25 holes for a bolt 26, which serves to secure both ears of the tie plate to the center brace; and I also provide in the tie plate a hole for the 70 caster shank 17 and holes for the bolts 19. 70

My improved tie plate secures the center brace 13 to the end brace 12 regardless of the bearing casting 18, and helps clamp the bearing casting in place. It is economically constructed and easily attached, and the fact 75 that it may be secured to the end braces by the same bolts which are used to bolt on the bearing casting prevents weakening the end brace due to drilling extra holes therein for the purpose of attaching the tie plate. The 80 tie plate also serves as a wearing plate which may be easily replaced when it becomes worn.

I claim as my invention:

1. A tie plate for a truck having a transverse end brace and a longitudinal center brace, said tie plate having a part arranged to be bolted against the outer face of said end brace, an intermediate part extending transversely below said end brace, and two 90 ears arranged to be bolted to opposite sides of said center brace.

2. A truck having an end brace, a center brace transverse to the end brace and spaced therefrom to provide an intervening space, 95 a bearing mounted on said end brace in said intervening space and adapted to engage said center brace and be held thereby securely against said end brace, a roller supported in said bearing, and a tie plate for 100 securing said center brace to said end brace, said tie plate comprising a portion adapted to extend across said intervening space and being attached to both said end brace and said center brace.

3. A truck having an end brace, a center brace transverse to the end brace and spaced therefrom to provide an intervening space, a bearing mounted on said end brace in said intervening space, a roller supported in said 110

bearing, and a tie plate for securing said center brace to said end brace, said tie plate comprising a portion adapted to extend across said intervening space and being attached to both said end brace and said center brace.

4. A truck having an end brace, a center brace transverse to the end brace and spaced therefrom to provide an intervening space, a bearing mounted on said end brace in said intervening space, a roller supported in said bearing, and a tie plate for securing said center brace to said end brace, said tie plate comprising a portion adapted to extend across said intervening space below said bearing and being attached to both said end brace and said center brace.

5. A truck having an end brace, a center

brace transverse to the end brace and spaced therefrom to provide an intervening space, a bearing mounted on said end brace in said intervening space, a caster, and a tie plate for securing said center brace to said end brace, said caster comprising an integral yoke and shank and a wheel rotatably mounted in said yoke, said shank being rotatably supported in said bearing, and said tie plate being attached to both said end brace and said center brace and having an intermediate portion lying between said caster-yoke and said bearing.

In witness whereof, I have hereunto set my hand at Indianapolis, Indiana, this 18th day of June, A. D. one thousand nine hundred and twenty three.

ROBERT L. DORSEY.
